CHARLES A. ERICKSON, OF CHICAGO, ILLINOIS.

SALES-CHECK HOLDER.

Application filed January 11, 1923. Serial No. 245,865.

My invention relates to combination holders and punches of the class commonly employed by waiters in restaurants or lunch rooms for holding pads of checks and for notching detached checks to indicate the amount of the patron's bill. In using such a combination check-holder and notcher, the waiter commonly holds the same in one hand while tearing the upper check off the pad 5 with the other hand, then inserts the selected charge-indicating part of the check in a notch of the notcher and thereafter actuates the notching member to effect a notching of the inserted portion of the check. For this purpose, the notcher usually has a slidably mounted notching member which is normally held in a retracted position by a spring within the casing of the notcher, so that the user must overcome the pressure of this spring in 10 addition to exerting sufficient power for cutting out an edge portion of the check or otherwise notching (or perforating) the check.

With checks made of tough material, the effort required for this double purpose is 15 considerable, and particularly so after wear has dulled the coacting portions of the notcher housing and of the punch of other notcher. Consequently, the user must hold the appliance so as to prevent the pressure on the 20 notching member (as transmitted through the spring) from bodily moving the casing of the notcher. With many forms of combined check-holders and notchers, this cannot easily be done, owing to the small size of the bottom of the notcher casing. Moreover, 25 such appliances commonly have the notcher offset from the holder, in order that the notcher may not project in alignment with the free end of the pad of checks where it 30 would interfere with the convenient grasping and detaching of a check from the pad.

To avoid such an interference with the detaching of the upper check, and also with the inserting of the pad in the holder, the 35 notcher when of a type employing a slide punch, is frequently mounted beyond one side of the pad of checks, and with the axis of the punch at right angles to the back of the holder on which back the pad rests. When 40 thus mounted, the notcher is difficult to operate with one hand while the other hand is holding the detached check in its proper position. This difficulty is encountered both

because the bottom of the notcher casing is 55 too small to have it rest on any considerable surface portion of the hand, and also because the off-setting of the notcher beyond the side of the holder causes the notch-effecting pressure to rock the entire appliance in the hand 60 which holds it. Such a rocking effect can be avoided by mounting the notcher behind the lower end of the back of the holder with its axis parallel to and extending transverse of the face of the pad of checks, but the other objection then is still encountered, namely 65 the quite small area of the notcher end against which a finger of the user's hand must press while the notching member is actuated by another finger of the same hand.

In one of its main aspects, my invention 70 aims to overcome both of these objections by providing such holders with thrust-receiving portions of considerable area; and by disposing these portions so that they will bear on convenient parts of the hand of the user, 75 but will not interfere with the speedy detaching and manipulating of the check which is to be notched.

In another aspect, my invention aims to 80 provide a novel appliance of this class, in which both the holder and the notcher casing can readily be formed from a single piece of sheet metal, and in which the single-piece formation can even include a spring tongue for latching the pad of checks in the holder. 85

Still further and also more detailed objects will appear from the following specification and from the accompanying drawings, in which

Fig. 1 is a front elevation of a combined check-holder and notcher embodying my invention and having the axis of the notcher parallel to the face of the pad of checks, showing a partially consumed pad of checks held by the holder. 90

Fig. 2 is a side elevation of the same appliance, taken from the right side of Fig. 1.

Fig. 3 is a longitudinal section taken along the line 3-3 of Fig. 1, with the pad of checks removed. 100

Fig. 4 is a transverse section, taken through Fig. 1 along the line 4-4 and looking upward. 105

Fig. 5 is a rear elevation of the appliance of Fig. 1.

Fig. 6 is a transverse section, taken along

the line 6—6 of Fig. 5 and looking downward.

Fig. 7 is a front elevation of another embodiment of my invention, with a pad of checks held by it, namely one in which the notcher casing is separately formed and is mounted with its axis transverse of the face of the checks.

Fig. 8 is a horizontal section, taken along the line 8—8 of Fig. 7 and looking downward.

Fig. 9 is a horizontal section, taken along the line 9—9 of Fig. 7 and looking upwards.

In the embodiment of Figs. 1 to 4 inclusive, the holder body, the casing of the notcher, and the pad-latching tongue are all formed from a single strip of sheet metal which for the greater part of its length corresponds in width to the back of the holder. This strip of metal is bent along transverse lines, as shown in Figs. 2 and 3, to form a flat back 1 (desirably longer than the pad of check 2), a top 3 and a downwardly directed flange 4 overhanging the upper end of the pad. The strip is also recurved below the lower end of the pad to form a tubular notcher 5 casing and a tongue 5 which extends in front of the back 1, which tongue has its upper end disposed behind the overhanging flange 4. The metal employed is preferably resilient and the upper end portion of the tongue 5 is bent forwardly from the main portion 5^A of the tongue, so that the tip of the tongue will be spaced from the flange 4 by a distance less than the thickness of the pad of checks, when no pad is supported by the holder. I also desirably form one or more rearwardly and upwardly directed fingers 6 from the flange 4, and I preferably locate the tips of these fingers and of the tongue 5 so that they will underhang the usual wire stapling 7 of the pad of checks, thereby latching the pad effectively in its inserted position. To stiffen the forwardly inclined portion 5 of the tongue for this purpose, while also providing the resiliency needed to facilitate an easy attaching or detaching of the pad, I preferably bow the major tongue portion 5^A forwardly away from the back and rigidly secure the tongue to the back below its said bowed portion—as for example, by providing the lower end of the tongue with lateral fingers 8 which are clinched respectively over the opposite edges of the back 1.

In the embodiment of Figs. 1 to 3, the casing of the notcher is formed from parts of original metal strip interposed between the strip parts which are formed into the back and the tongue. These connecting portions are bent to form a casing top 9 leading rearwardly from the lower end of the back 1 to a casing back 10, which back is connected by a vertically V-sectioned front 11 to a casing front 12 extending in vertical alinement with the lower end of the tongue. Slidably mounted in this casing is a punching or notching member 13 which normally is kept to the right

of the notch 14 in the notcher casing (in Fig. 1) by a spring 15 within the casing, but which may be slid to the left by digital pressure on the head 16 of the notching member. A tongue 17 formed from the notcher casing 70 limits the outward sliding of the notching member, and an end finger 18 on the casing engages the end of the spring at the left-hand end of the casing in Fig. 1, while the other end of the spring engages the inner 75 face of the head 16, as more fully disclosed in my copending application No. 245,866, filed January 11, 1928, on a check notcher.

In using the above described appliance, the forward check is torn off the pad 2 and the selected charge-numeral edge portion of the check is inserted in the notch 14 of the notcher casing, after which the notching member is slid toward this notch (or toward the left in Fig. 1) to notch this selected portion of the check. During this notching, the digital pressure on the head 16 of the notching member must be resisted and, since the notcher has its axis offset from the holder (as shown in Fig. 2) the notch-effecting pressure will tend to rotate or twist the entire appliance in the hand which holds it. To avoid this, I provide a thrust-resisting flange 19 extending at right angles to the back 1, which flange desirably has its outward face in alinement with the end of the notcher casing toward which the notching member is moved. This flange is here shown as constituting the original free edge portion of a part formed from the back 1 of the holder, this part being bent 90 so that a wall portion 20 connects it with the back 1 and so that the free edge of the flange 19 butts against the said back.

With this provision, the thrust-receiving flange 19, even though spaced longitudinally 105 of the holder from the notcher casing, can be substantially flush with the open end of the notcher casing and rigidly at right angles to the axis of that casing, as shown by Fig. 6. Consequently, the user who holds my appliance in his hand has the flange 19 resting flatwise on a portion of the hand where it squarely resists the thrust of the spring during the inward forcing of the notching member, thereby eliminating any twisting of 115 the holder in the hand of the user. With the notcher extending transversely across the bottom of the casing, I preferably have the check-admitting opening or notch 14 in the notcher casing directed downwardly, but I 120 do not wish to be limited to this particular position of the said opening.

Moreover, while I have heretofore described my invention in an embodiment in which the notcher casing is integral with the holder body, in which the axis of this casing is parallel to the back of the holder, and in which the notcher is of the general type described in my said copending application, I 125 do not wish to be limited in these respects. 130

Obviously, many changes might be made without departing either from the spirit of my invention or from the appended claims.

For example, Figs. 7 to 9 show an embodiment in which the back 1 has at its lower end a lateral wing 21 which is recurved to overlie the back and which wing supports a tubular punch casing 22, while a punch 23 is slidable in this casing by pressure on the head 24 which is normally raised by a spring 25. In this embodiment of my invention, the thrust-receiving flange 26 extends laterally from the back 27 and in alignment with the latter, and this flange is shown as continued by a forward flange 28 leading to a downwardly directed portion 29 which abuts against the forward face of the flange 26. With the rear faces of the flange 26 and the back of the holder substantially in alignment and at right angles to the axis of the punch, the hand of the user can readily resist the pressure exerted during the notching operation, so as to keep the appliance from rocking or twisting in his hand.

With each of these embodiments, it will be noted from Figs. 4 and 8 that the thrust-resisting flange is one wall of a tubular formation with its other walls disposed for bracing the projecting flange, thus affording adequate stiffness. Furthermore, by rounding the connections between these walls at the outer edge (namely, between the walls 19 and 20 of Fig. 4 and between the walls 26 and 28 of Fig. 8) I avoid having the hand of the user grasp a sharp edge. However, I do not wish to be limited in this respect, nor do I wish to be limited to the use of the various novel features of my invention in conjunction with one another.

I claim as my invention:

1. In a holder for a pad of checks, a body member made of a strip of resilient metal doubled on itself intermediate of its length to form a tongue overlying a back, the free end of the back being recurved to overhang the free end of the tongue, the tongue being bent so that its free end is spaced away from the back by a distance normally less than the thickness of the pad of checks, the tongue having a portion thereof clinched to the back at a considerable distance from the free end of the tongue; the tongue having a portion adjacent to the said clinching, but terminating short of its free end, bowed away from the back.

2. In a holder for a pad of checks, a body member made of a strip of resilient metal doubled on itself intermediate of its length to form a tongue overlying a back, the free end of the back being recurved to overhang the free end of the tongue, the tongue being bent so that its free end is spaced away from the back by a distance normally less than the thickness of the pad of checks, the tongue having a portion thereof clinched to the back.

at a considerable distance from the free end of the tongue; the tongue having a portion thereof clinched to the back at a considerable distance from the free end of the tongue; the said clinching being spaced from the line 70 along which the strip is doubled and the intermediate portion being formed into a tubular casing for a check notcher.

3. In a holder for a pad of checks, a body member made of a strip of resilient metal 75 doubled on itself intermediate of its length to form a tongue overlying a back, the free end of the back being recurved to overhang the free end of the tongue, the tongue being bent so that its free end is spaced away from the back by a distance normally less than the thickness of the pad of checks, the tongue having a portion thereof clinched to the back at a considerable distance from the free end of the tongue; the tongue having fingers at 80 its opposite edges, and at a considerable distance from the free end of the tongue, clinched over the back.

4. In a holder and notcher for a pad of checks, a body member comprising a metal 90 strip extending behind the pad of checks and provided at its upper end with means for gripping the pad, the said strip being recurved at its lower end to form a tubular notcher housing having a wedge-shaped edge 95 provided with a notch into which a detached check may be inserted; and a notcher slidably mounted in the said housing and adapted to notch the inserted check.

5. A holder and notcher as per claim 4, in 100 which the recurved portion of the said strip is secured above and near the said housing to the part of the strip which extends behind the pad of checks.

6. A holder and notcher as per claim 4, in 105 which the recurved portion of the strip has a finger formed from it to afford a partial closure for one end of the housing, in combination with a spring interposed between the notcher and the said finger for retracting the 110 notcher.

7. A holder and notcher as per claim 4, including a flange extending transversely from the back substantially in alignment with the end of the notcher housing toward which 115 the notcher is slid during the notching of the inserted check.

8. A holder and notcher as per claim 4, in which the notcher housing has its axis rearward of the tongue, including a flange extending rearwardly transverse of the back in substantial alignment with the end of the notcher housing toward which the notcher is slid during the notching of the inserted check.

9. A combined holder and notched for a 125 pad of checks, comprising a holder including a back overlapped by the pad, and a notcher disposed beyond one edge of the back, the notcher including a housing and a notching member slidable in the housing; 130

the holder having a flange spaced from and at right angles to the direction in which the notching member is slidable, the flange being substantially in alignment with the end of the notcher housing toward which the notching member is slid during the notching of a check.

10. A combined holder and notcher for a pad of checks, comprising a holder equipped at its upper end for grasping the pad, a

notcher casing carried by the lower end of 10 the holder and having its axis behind the back of the pad and parallel to the face of the pad, and a notching member slidably mounted in the notcher casing.

Signed at Chicago, Illinois, January 7, 15
1928.

CHARLES A. ERICKSON.
